UNITED STATES PATENT OFFICE.

GEORGE O. THOMPSON, OF GLENDALE, CALIFORNIA.

GAS WATER HEATER.

Application filed May 31, 1923. Serial No. 642,712.

To all whom it may concern:

Be it known that I, GEORGE OTIS THOMPSON, a citizen of the United States, residing at Glendale, in the county of Los Angeles and State of California, have invented new and useful Improvements in Gas Water Heaters, of which the following is a specification.

My present invention is a gas water heater; and it is a primary object of this invention to provide a heater which may be manufactured and sold at a moderate price and which shall nevertheless be highly efficient and economical in the heating of water by the combustion of a gaseous or liquid fuel.

It is a further object of this invention to provide a water heater which may comprise concentric shells and which shall occupy a minimum of space and shall require no extensive or difficult connections or coils.

It is a further object of this invention to provide a water heater which may be substantially circular in cross section and which shall comprise a hollow "boiler" so arranged as to permit the passage of combustion or flue gases therethrough, my preferred construction being such as to comprise staggered baffles extending across said central flue and provided also with aligned apertures for substantially vertical pipes, which are thus effectively exposed to receive heat from said gases, the mentioned pipes being preferably connected at top and bottom to suitable header castings respectively provided with outlet and inlet connections extending to said boiler.

It is a further object of my invention to provide a gas water heater requiring no laterally connected pipes, the heating circuit comprising only the boiler itself and the mentioned parallel vertical heating pipes extending therethrough, and suitable connections, both the interior walls of the boiler proper and the mentioned parallel pipes being exposed to hot gases and only an unavoidable minimum of heat being permitted to escape from the outside of the boiler and from the top thereof, the preferred construction of my boiler being such as to permit of the connecting of a stack thereto and such that an entire set of parallel heating pipes connected to manifolds and associated with baffles may be assembled and inserted, or removed for repair or renewal, as a unit.

Other objects of my invention will appear

from the following description of a preferred embodiment thereof, and from the appended claim, taken in connection with the accompanying drawings, in which—

60

Fig. 1 is an elevation, with parts broken away.

Fig. 2 is a section, which may be regarded as taken on the line 2—2 of Fig. 1.

Figs. 3 and 4 are respectively elevational and plan views of a preferred novel type of header casting, suitable for use in my invention.

Referring in detail to the parts of that specific embodiment of my invention which I have chosen for purposes of illustration, 1 is a boiler comprising an inner shell 2 and an outer shell 3, the latter being extended at the bottom to form a skirt 4, which may be integral therewith and may be provided with supporting legs 5 and with a door 6, to permit access to parts hereinafter referred to, the shells 2 and 3 being connected at the top by an annular plate 7, provided with two openings 5^a and 6^a, and connected at the bottom by a similar plate 7', provided with a single opening 8, to facilitate the connecting of heating pipes in the manner hereinafter described.

Water may be introduced into my boiler in any suitable way, as by means of an inlet pipe 9, which may extend nearly to the bottom thereof, in a well known manner; and, although various alternative constructions might obviously be employed, I prefer

80

to provide novel circulating means comprising headers 10 and 11 which may be substantially alike and may be connected by parallel pipes or tubes 12, shown as extending throughout the effective length of the

85

boiler 1 and as associated with a plurality of aligned baffles. The mentioned baffles may advantageously be of two types, one type being provided with a central aperture, which may be approximately three inches in

90

diameter and may permit the passage of a central group of pipes, shown as four in number, and as secured to openings 13, directly in the faces of the respective headers, and the other set of baffles, alternating with

95

those mentioned and suitably spaced therefrom, may be of such size as to provide a circumferential passage for hot gases, adjacent to the inner walls 2 of the boiler 1.

100

The respective headers 10 and 11 may be connected with the interior of the boiler in any suitable way; but I prefer to connect

105

110

the lower manifold 10 by means of a pipe 14, which may extend vertically through a burner 15 and may be threaded into a single central aperture in the bottom of said header, this pipe 14 being shown as connected by means comprising a union 16 in a horizontal pipe 17 with a vertical pipe 18 extending into the mentioned opening 8 in the bottom of the boiler 1, the pipe 18 being preferably provided with a downward extension 19 having a cock or faucet 20, to permit a complete withdrawal of water from the heater, when desired for purposes of cleaning, repair, or the like.

It being understood that when the burner 15 is lighted, convenient access being provided through the door 6, the heating of water in the header 10 and the pipes 12 will promote an upward circulation therein, I facilitate this circulation by providing a single vertical pipe 21 connected with the upper face of the header and leading, by a horizontal connection 22, preferably provided with a union 23, into a vertical pipe 24, which may serve not only as a circulation pipe, through which hot water may descend into the boiler 1, but also as a delivery pipe through which hot water may be withdrawn, as required, for use throughout a dwelling, or the like.

Although the headers 10 and 11 might be otherwise formed, I find it especially advantageous to provide headers in the form of brass castings comprising a central body 25 and divergent branches 26, respectively provided with parallel openings 27, the central body being also provided with the mentioned openings 13 directly in one face thereof and with a central opening 28 in the opposite face thereof, this central opening serving, in the case of the lower header, to provide a means for connecting the pipe 14, and serving, in case of the upper header, as a means for connecting the pipe 21.

In an installation of the general character shown in the drawing, such an installation being adapted to the uses of an ordinary household, the baffle plates above referred to may be seven in number, and each baffle plate may be secured by means of collars provided with set screws engaging the tubes 12, it being understood that those baffles 29, which are provided with central apertures, should fit tightly against both the tubes 12 and the wall 2 of the boiler 1, whereas the baffles 30, which have no central apertures, may be spaced a quarter of an inch or more from the wall 2, although they may fit snugly upon the tubes 12, my preferred con-

struction being such as shall retard the rise 60 of combustion gases through the interior of my boiler and such as shall facilitate the heating thereby of both the tubes 12 and the wall 2, whereby circulation of the water will be promoted and even the water in the 65 lower part of the boiler 1 will be appreciably warmed, although the hottest water will be at the top of the boiler, where it may be readily withdrawn, as desired.

Although I have herein described one 70 complete embodiment of my invention, it will be understood that various features thereof might be independently employed and also that various modifications might be made therein without departure from the 75 spirit and scope of my invention as the same is indicated above and in the following claims, the use of a stack above the top of the boiler being optional.

The headers 10 and 11 connected by the 80 pipes 12 and carrying the baffles 29 and 30, the pipe 14 connected to the header 10 and the pipe 21 connected to the header 11, forms a heating unit which is readily inserted into the boiler and connected to the 85 boiler by the unions 16 and 23, and which is readily removable from the boiler by breaking the unions 16 and 23.

What I claim is:

A water heater comprising an outer shell, 90 an inner shell disposed within the outer shell, means providing end closures between the shells, headers disposed adjacent the top and bottom of the inner shell, a plurality of straight, parallel tubes disposed within 95 said inner shell connecting said headers, a conduit having a union therein connecting the upper header to the space between the shells adjacent the top thereof, a conduit having a union therein connecting the lower 100 header to the space between the shells adjacent the bottom thereof, said unions providing for removal of the headers and pipes, means for supplying and withdrawing water from the space between the shells, a heating 105 element disposed beneath the lower header, there being shoulders provided upon said pipes, and baffle plates resting upon said shoulders, alternate baffle plates having their peripheral edges in spaced relation to the 110 interior surface of said inner shell, and the intermediate baffle plates having their peripheral edges engaging the inner shell and having apertures therethrough.

In testimony whereof I have signed my 115 name to this specification.

GEORGE O. THOMPSON.
